UNITED STATES PATENT OFFICE.

WILLIAM H. CROSBY, OF PARISH, NEW YORK.

IMPROVEMENT IN CORN-PLANTERS.

Specification forming part of Letters Patent No. 126,788, dated May 14, 1872.

Specification describing an Improved Corn-Planter, invented by WILLIAM H. CROSBY, of Parish, in the county of Oswego and State of New York.

The invention relates to that class of corn-planters where two rows are planted simultaneously; and it consists in the improvements hereinafter described, in connection with all that is necessary to a full understanding thereof, and subsequently pointed out in the claim.

Figure 1 is a top view. Fig. 2 is a side view. Fig. 3 is a detail view.

A represents the double planter, having the pole B pivoted to axle. C C are frames for the hoppers D D, the slides E E, and their operative mechanism. Beneath the hopper are delivery-spouts and opening and covering plows, constructed and arranged in the usual manner. Each slide E is operated by a train of mechanism, consisting of spring-retracted lever e , a lever, e^2 , and connecting-link e^1 . The lever e^2 is operated by a projection on the sliding clutch-sleeve F. This sleeve and the boss of the wheel G are correspondingly ratcheted. The sleeve F is also provided with a spring, f, which throws it into gear with the wheel by which it is revolved. J is a lever, bifurcated at the end and embracing an annular depression in the sleeve F. By pressing this lever forward the sleeve is thrown out of connection with wheel and the seeders cease to drop. This is done at the end of each row while the machine is being turned around. The two frames C C are independent of each other, and

are intended to be raised separately to regulate the depth of planting, or when either encounters an obstacle which impedes its progress. The means by which this is effected consist of the caster-wheels K having standards k, which pass up through the frames, and which are provided with the levers k^1 , pivoted on the top thereof. These levers have grooved cams k^2 , over which are placed cords or chains k^3 , connected with the ends of plates c. By this means the frame is caused to slide upon the standards k when the opening-plow is intended to run shallow, and vice versa. L is a rod, which rests at each end in a slotted plate, c, and forms a rest for supporting the pivoted axle, while it is provided with a middle guide-frame, l, which prevents lateral movement, but allows vertical play in backing or turning.

These devices render a double seeder very convenient, and allow the seed to be planted with great uniformity.

Having thus described my invention, what I claim as new, and desire to secure by Letters Patent, is—

The frames C C, independently pivoted to axle, pivoted in front to rod L, and supported by caster-wheels K K, in combination with tongue B, as described, so as to allow said frames to rise separately when in contact with obstructions.
